UNITED STATES PATENT OFFICE.

HOSEA W. LIBBEY, OF BOSTON, MASSACHUSETTS.

COMBINED WINDOW-SCREEN AND VENTILATOR.

SPECIFICATION forming part of Letters Patent No. 338,278, dated March 23, 1886.

Application filed August 6, 1885. Serial No. 173,701. (No model.)

To all whom it may concern:

Be it known that I, HOSEA W. LIBBEY, a citizen of the United States, residing at Boston, in the county of Suffolk and State of Massachusetts, have invented a new and useful Improvement in a Combined Window-Screen and Ventilator, of which the following is a specification.

The object of my invention is to provide a window-screen and ventilator particularly applicable for steam-cars, by means of which fresh air is admitted into the car, while dust, smoke, &c., are excluded, and that without materially interfering with the view.

The invention consists of a suitable frame adapted to fit into the window-opening and divided into sections, one or more of which are fitted with glass, and the others with a double wire gauze or netting with a layer or thickness of sponge or other suitable absorbent material between, one of the wire-gauze sides being provided with pins for holding the sponge and made removable, so that it with the sponge can be removed for being cleansed and readily replaced.

Referring to the accompanying drawings, Figure 1 is a longitudinal vertical section of a portion of a steam-car fitted with my invention. Figs. 2 to 5 are views showing frames with various arrangements of the glass and wire-gauze, an elevation, vertical and longitudinal section, of each being shown. Figs. 6 and 7 are respectively elevation and a vertical section of a portion of the frame and wire-gauze provided with pins.

A represents a portion of a steam-car, and B the windows.

C are light wooden frames made to fit into the opening between the window-sill and the lower part of the sash when the latter is raised. The frames are fitted at each end with suitable packing, a, preferably of small rubber tubing, so that when placed in position the tubing will expand and fill out the groove in which the sash slides and prevent any dust or smoke from entering.

Each of the frames C is divided into sections by cross-bars b, one or more of these sections being fitted with glass D, and the other sections being covered on their outer sides by wire gauze or netting E, secured to the frame

C and to cross-bars b. The inner sides of these sections are closed by wire gauze or netting E', secured to light frames F, that are held onto the frames C by means of buttons, bolts, or other suitable fastening, and the inner side of the netting E is provided with a series of pins, f, (see Figs. 6 and 7,) on which is placed sponge or other suitable absorbent material, G, preferably cut into layers of the required thickness.

When required for use, the sponge or other suitable absorbent material is moistened with water and the frame inserted into the window-opening, the sash being drawn down to rest on the top of the frame A. Air will then percolate through the wire gauze or netting and through the sponge or other absorbent material, which being wet will arrest all smoke, dust, dirt, &c., thereby keeping the car supplied with clean fresh air, while the glass D admits of an uninterrupted view.

When required for ventilation only—such as in the monitor-top H, or beneath the windows—the frames C may be covered on both sides entirely with wire-gauze and the whole space between be filled with sponge or other suitable absorbent material, and they may be made to slide in suitable grooves or otherwise secured, so that they can be readily removed to be cleansed and replaced again; or they may be secured on the outside of the car and the openings on the inside of the car covered by registers, so that air may be admitted or shut out, as desired.

In Figs. 2, 3, and 4 I have shown the frames C as being flat with the cross-bars b arranged in different ways, and in Fig. 5 I have shown the frame in the form of a bay, so that the central portion will project a short distance from the side of the car, thereby causing the sides to be at an angle, and when the car is in motion the wind will strike against and percolate through the forward side of the frame, thus giving a greater supply of fresh air.

The bay shown in Fig. 5 may be inverted—that is, made to project slightly into the car—in which case the wind will strike and enter at the rear side of the frame.

It will be seen that by having the wire gauze or netting E' secured to the frame F it can be taken out of the main frame and with it the sponge or other absorbent material held by

the pins *f*, so that the sponge may be cleansed, after which it can be replaced in the main frame.

What I claim as my invention is—

- 5 1. A window-screen and ventilator composed of a frame divided into sections, one or more of which are fitted with glass, and one or more with wire gauze or netting on each side, the space between said netting being filled with a sponge or other suitable absorbent material, substantially as shown and described.
2. A wire gauze or netting, *E*, provided

with pins *f*, for holding sponge or other suitable absorbent material, in combination with a frame having one side covered with wire 15 gauze or netting, substantially as shown, and for the purpose described.

In testimony whereof I have signed my name to this specification in the presence of two subscribing witnesses.

HOSEA W. LIBBEY.
